CLAIM

The ornamental design for a watch buckle, as shown and described.

DESCRIPTION

FIG. 1 is a front perspective view of a watch buckle in its disassembled state, showing my new design;

FIG. 2 is a rear perspective view thereof in its disassembled state;

FIG. 3 is a front view thereof in its disassembled state;

FIG. 4 is a rear view thereof in its disassembled state;

FIG. 5 is a left side view thereof in its disassembled state;

FIG. 6 is a right side view thereof in its disassembled state;

FIG. 7 is a top view thereof in its disassembled state;

FIG. 8 is a bottom view thereof in its disassembled state;

FIG. 9 is a front perspective view thereof of its assembled state;

FIG. 10 is a rear perspective view thereof of its assembled state;

FIG. 11 is a front view thereof of its assembled state;

FIG. 12 is a rear view thereof of its assembled state;

FIG. 13 is a left side view thereof of its assembled state;

FIG. 14 is a right side view thereof of its assembled state;

FIG. 15 is a top view thereof of its assembled state;

FIG. 16 is a bottom view thereof of its assembled state;

FIG. 17 is a perspective view shown with environmental structure; and,

FIG. 18 is an enlarged detail view of area 18 in FIG. 1.

The broken line showing of a strap in FIG. 17 is for the purpose of illustrating environmental structure and forms no part of the claimed design.

The dash-dot-dash broken boundary lines encircling a portion of the watch buckle in FIG. 1 and illustrated in the enlarged view in FIG. 18 form no part of the claimed design.
